INVENTOR
Henry E. Leppert,
BY
K. W. S. ATTORNEY

UNITED STATES PATENT OFFICE.

HENRY E. LEPPERT, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

Application filed January 14, 1926. Serial No. 81,134.

My invention relates particularly to switches adapted to be used in panel board constructions.

The invention is particularly directed to 5 the method of mounting the cover plate in position on the switch but positively insulated from the switch and its supporting frame.

In former constructions the cover plates are not insulated from the switch frames 10 and, in such cases, it is necessary to ground the switches. Such grounding of the switches or switch frames frequently causes the switches to arc and burn up.

The main object is to provide a construction 15 in which the cover plates are securely mounted and yet insulated from the switches and the necessity for grounding the switches is obviated.

In order to accomplish this result, I provide 20 a switch frame with insulating plates which carry the necessary bushings for securing the cover plate in position but which insulate the cover plate from the switch and obviate the necessity for grounding the 25 switch.

Fig. 1 is a front view of a cover plate and switch illustrating one embodiment of my invention.

Fig. 2 is a detail edge view, partly in section, showing one form of switch provided 30 with a cover plate.

Fig. 3 is a side view and section of the structure shown in Fig. 2 but with the cover-plate removed.

Fig. 4 is a perspective view of the separated insulating plates and the supporting frame.

Fig. 5 is a plan view of a modified form of insulating plate.

Fig. 6 is a sectional view showing the connection of this form of plate to the frame.

As shown in the drawings the switch is of the toggle or lever type with an operating handle or lever 7, but the construction is 45 equally well adapted for use with other switches, for instance push button switches.

In this construction there is a base plate 8, for instance, of sheet metal, to which is attached the central part of a bracket member 9 provided with supporting lugs 10 and 11 at opposite ends. The switch proper has a supporting frame or yoke 12 adapted to be supported on the lugs 10 and 11 and secured

thereto in suitable manner, for instance, by screws, bolts or rivets 13. The movable contact member 14 may be of any suitable construction adapted for operation as usual through handle 7 and a suitable toggle or by push buttons or the like.

The stationary contacts 15, which are 60 commonly termed high contacts are provided with feet, such as 16, suitably secured to the base plate or base 8, but insulated therefrom. In this panel board type of switch, each of the contacts 15 is electrically 65 connected with a plate 17 adapted to be supported on a bus-bar, the foot of the contact being connected with the base 8 by means of rivet 19 which passes through an insulating plate 20 between the foot 16 and the plate 8 70 and through an insulating plate 21 between the plate 8 and the plate 17. Other stationary contact members 22 may be provided at the opposite end of the switch. In the present construction the plates 20 and 21 extend 75 the full length of the switch. Contact 22 may be secured to a terminal plate 18 by a rivet 23.

In the present construction, the frame or yoke 12 has two side plates each provided 80 with a pivot 24 to furnish pivotal support for the contact member 14. Each side plate is provided with spaced lugs 25 which extend through openings 26 in an anchor plate 27 of insulating material, preferably of 85 insulating fibre, the plate being secured to the switch frame by riveting such lugs 25 so as to rigidly hold the plate in place. Mounted on the insulating plate 27 is another insulating plate 28 having openings 29 which 90 register with openings in plate 27 to receive hollow rivets 30, the rivets being upset to permanently secure the plates 27 and 28 together and to the switch frame as a unit. The plates 27 and 28 are provided, of course, 95 with registering openings 31 and 32 to accommodate the handle 7.

The cover or face plate 33 has an opening 34 for each switch handle. The cover plate may be secured to the switch by screws 35 100 passing through perforations in the cover plate and screwed into the hollow rivets 30. The plate 28 covers the lugs 25 on the switch frame and insulates the switch frame from the cover plate 33. The plate 27 serves as an 105 intermediary means for securing the plate

28 to the switch frame and co-operates with plate 28 and rivets 30 to form a support for the cover plate 33 as well as a positive means for insulating the cover plate from the switch frame or any part of the switch. In this construction it is not necessary to ground the switch as it is perfectly insulated.

The modified form of insulating plate shown in Figs. 5 and 6 is a single plate 27' of approximately the same thickness as the two plates 27 and 28 shown in Figs. 2, 3 and 4. This single plate is perforated to receive the switch operating handle 7, the lugs 25' of the switch frame and the bushings 30. The lugs 25' of the switch frame extend only part way through the holes in the plate 27' and are upset or headed over in the holes so that there is no possibility of contacting with the cover plate 33. The bushings 30 are upset or riveted in corresponding holes in the plate 27' provided they are to be used but, in case the material of the plate is of a suitable character, the bushings 30 may be omitted by piercing the plate with suitable holes and then threading the holes to receive the cover securing screws 35.

While I have shown preferred embodiments of the invention, it should be understood that various changes therefrom may be made without departing from the spirit and scope of the invention.

I claim:

1. The combination of a snap switch frame having side plates, an insulating top plate formed of hard fibre united to said side plates, and threaded bushings secured to said fibre top plate and providing seats for cover fastening screws.

2. A snap switch having side plates, an insulating top plate united to said side plates, and internally threaded bushings united to said top plate and spaced away from said side plates for receiving cover securing screws.

3. In a switch construction, switch operating means, a switch frame having lugs, an insulating plate secured to said frame by said lugs, a second insulating plate overlying and secured to the first plate to shield said lugs, and means for securing a cover plate to said insulating plates.

4. In a construction of the character described, switch operating means, a switch frame having fastening lugs, an insulating plate secured to said lugs, a second insulating plate secured to said first plate to shield the ends of said fastening lugs, and means for securing a cover plate to said insulating plates.

5. In a construction of the character described, switch operating means, a switch frame having an extended upper portion adjacent said switch operating means, an insulating plate on said extended upper portion, lugs extending through said plate to fasten the same to said extended portion, a second insulating plate on the first plate and covering said fastening plugs, and means for securing a cover plate to said insulating plates.

6. In a construction of the character described, a switch frame having projecting lugs, an insulating plate secured to said frame by said lugs, a second insulating plate on the first plate and covering said lugs, hollow rivets securing said plates together and threaded internally, a cover plate, screws passing through said cover plate and into said hollow rivets, and a switch handle extending through said insulating plates and said cover plate.

7. In a construction of the character described, a switch frame, a substantially flat insulating member of fibrous character, means for fastening said member on said frame including lugs extending part way through and upset in said member, and a cover plate secured to said insulating member.

8. In a construction of the character described, a switch including a frame, a substantially flat insulating member, means including devices extending part way through said member for securing said member on said frame, a cover plate, and means for fastening said cover plate to said insulating member at points spaced away from said switch and said frame, said fastening means including bushings secured into said insulating member and screws passing through said cover plate and seated in said bushings.

HENRY E. LEPPERT.
